UNITED STATES PATENT OFFICE.

ROBERT D. DUNCAN, JR., OF EAST ORANGE, NEW JERSEY, ASSIGNOR TO WIRED RADIO INC., OF NEW YORK, N. Y., A CORPORATION OF DELAWARE.

METHOD OF CARRIER-FREQUENCY SUPPRESSION.

Application filed May 19, 1925. Serial No. 31,393.

To all whom it may concern:

Be it known that I, ROBERT D. DUNCAN, Jr., a citizen of the United States, residing at East Orange, in the county of Essex and 5 State of New Jersey, have invented a certain new and useful Improvement in a Method of Carrier-Frequency Suppression, of which the following is a specification.

My invention relates broadly to radio 10 transmission systems, and more particularly to a method of suppressing the carrier wave frequency in radio transmission.

One of the objects of my invention is to provide a method of suppressing the transmission 15 of the unmodulated component of the carrier wave both during and intermediate the signaling or modulating periods.

A second object of my invention is to provide a method of incompletely suppressing 20 the transmission of the unmodulated component of the carrier frequency both during and intermediate the periods of modulation.

A third object of my invention is to provide a signaling system particularly adapted 25 for modulating frequencies covering the voice range and the musical scale, in which the unmodulated carrier frequency component may be suppressed at the transmitting station by circuit arrangements which I provide associated with the modulating system. 30

Another object of my invention is to provide a three phase high frequency generating or amplifying system at a transmitting station which is arranged to act upon a load circuit, with modulation means effective 35 upon one of the phases of the high frequency generating or amplifying system to cause the flow of high frequency current in the load circuit, such as an antenna or a line wire system, only during the period of modulation, the arrangement of circuits being such that when modulation is not taking place no current will flow in the load circuit, i. e., both during and intermediate the modulating periods the unmodulated component of the carrier frequency is substantially suppressed. 40

Still another object of my invention is to provide a multi-phase source of high frequency oscillations arranged to be modulated by a source of energy whereby signaling energy may be impressed upon a radiating antenna system or a carrier wave line wire system only during the modulation periods without transmission of a carrier 45

wave intermediate the modulation periods.

A still further object of my invention is to provide a system of telephone communication wherein a three phase frequency source is employed establishing equal high frequency voltages having different phases which are balanced in such manner that in the absence of modulation, current will not flow in the load circuit, but being arranged in such manner that when modulation takes place the balanced condition of the three phase source becomes disturbed and completely modulated high frequency current from the main source appears in the load circuit, thereby enabling the transmission of energy during periods of modulation while the unmodulated carrier frequency component is prevented at all times from reaching the load. 60

My invention may be applied to various 75 types of carrier wave transmission systems, that is, systems which relate to the transmission of signals by radiation from an antenna system through space for reception at any number of outlying stations or the 80 transmission of signals over line wire systems, such as telephone, electric light, power, and other lines for reception at receiving stations associated with the line at various points. 85

I effect the elimination of the carrier frequency transmission by means located at the transmitting station. My system as herein described is generally applicable both in space radio and wired radio, and I intend 90 no limitations upon the uses to which my invention may be applied. It is desirable in communication systems to eliminate the carrier frequency both from the viewpoint of increasing the efficiency of transmission 95 and for decreasing interference normally offered by the existence of the carrier frequency. I am aware of the Carson "push pull" amplification method of suppressing the carrier frequency but I depart radically 100 from the Carson method as will be more fully pointed out hereinafter. I have particularly described my invention in connection with radio telephone communication systems.

It is fundamental and well known in the 105 art of radio telephony that during modulation a band of high frequencies instead of a single frequency is transmitted. The width of this band depends upon the number of single frequency components contained in 110

the modulating source. For example, in the voice the single frequency components may extend from 100 to 3000 cycles while with music the range may be from 15 to 10,000 cycles per second. For purposes of discussion it is convenient and usual to consider only a single frequency modulating source from which conclusion may be drawn, which may be modified as required to conform to the condition of a frequency band instead of a single frequency.

Expressed mathematically, a carrier fre-

25 That is, with single frequency modulation the modulated wave will consist of three components, viz: The unmodulated carrier component and two modulated components consisting respectively of the carrier frequency plus and the carrier frequency minus the modulating frequency. In actual radio telephony of course instead of a single frequency modulating source there will be a band of frequencies and under this condition equation (2) is altered in the following respects:—The first term ($E_1 \sin \omega t$) remains unchanged. The second and third terms change from single frequency terms to terms each consisting of a series of frequencies, respectively representing the carrier frequency plus and the carrier frequency minus each of the low frequency components of the modulating source. There will then be transmitted the main frequency or unmodulated component, represented by the first term in (2) and two bands of frequencies falling above and below the main frequency.

frequency $E_1 \sin \omega t$ if modulated by a low single frequency $K \sin \rho t$ may be written in the well known form

$$(1) \quad e = E_1 (1 + K \sin \rho t) \sin \omega t$$

in which

$$0 \leq K \leq 1$$

is the "percentage of modulation", and $\omega = 2\pi \times$ high frequency and $\rho = 2\pi \times$ modulating frequency. By trigonometric transformation equation (1) may be rewritten as follows:

$$(2) \quad e = E_1 \sin \omega t + \frac{KE_1}{2} \cos(\omega - \rho)t - \frac{KE_1}{2} \cos(\omega + \rho)t$$

For some purposes it is very desirable to suppress the main or unmodulated carrier frequency ($E_1 \sin \omega t$ of equation 2), that is, to prevent its transmission. In which case, equation (2) will develop into

$$(3) \quad e' = \frac{KE_1}{2} \cos(\omega - \rho)t - \frac{KE_1}{2} \cos(\omega + \rho)t$$

which is seen to be composed of only two terms. Under the assumption that the modulating source contains a plurality of frequencies equation (3) would develop into two general terms, each consisting of a series of single frequency components, as noted previously. All of these facts are well known in the radio art.

Now in a three phase high frequency system three alternating voltages of equal amplitude but differing in phase by 120 degrees, if acting simultaneously upon a single circuit will produce a resultant voltage of the form.

$$(5) \quad \begin{aligned} e &= E \sin \omega t + E \sin(\omega t - 120^\circ) + E \sin(\omega t - 240^\circ) \\ &= E \sin \omega t - 0.5E \sin \omega t - 0.866E \cos \omega t \\ &\quad - 0.5E \sin \omega t + 0.866E \cos \omega t = 0 \end{aligned}$$

75 that is, the component voltages balance themselves out to zero. If now modulation is effected upon one of the three single

phase components, for example, the first term of (5), the latter may be written in the form

$$(6) \quad e' = E(1 + K \sin \rho t) \sin \omega t + E \sin(\omega t - 120^\circ) + E \sin(\omega t - 240^\circ)$$

By trigonometric transformation equation (6) develops into

$$(7) \quad e' = E \sin \omega t + KE \sin \rho t \sin \omega t - 0.5E \sin \omega t - 0.866E \cos \omega t - 0.5E \sin \omega t + 0.866E \cos \omega t$$

or

$$(8) \quad e' = KE \sin \rho t \sin \omega t$$

or

$$(9) \quad e' = \frac{KE}{2} \cos(\omega - \rho)t - \frac{KE}{2} \cos(\omega + \rho)t$$

which is identical with equation (3), the latter resulting from equation (1) when the

110 unmodulated component of the carrier frequency is suppressed. That is, if a balanced three phase high frequency generating or amplifying source is made to act in the proper manner upon a single circuit, for example, a radio antenna system or a pair of telephone or electric light wires, and

modulation by voice or otherwise, is effected upon only one of the phases, the result is that high frequency current will exist in the load circuit, antenna system, or wires, 5 only during the period of modulation; the amplitude of this current is directly proportional to the percentage of modulation K . If modulation is not taking place $K=0$, and no high frequency current flows. The 10 main carrier frequency is thus suppressed.

My invention will be more clearly understood by reference to the accompanying drawings, in which:

Figure 1 illustrates my invention as applied to a space radio transmission system; Fig. 2 is a vector diagram illustrating the displacement of the high frequency voltages generated at the transmitting station; and Fig. 3 illustrates a modified arrangement of 20 transmission system embodying the principles of my invention and showing the energy delivered to any type of load representative of a wired radio or space radio system.

Referring to the drawings in detail: In 25 Fig. 1, I have shown an electron tube transmission system, in which reference character 1 represents a three phase high frequency generator as, for example, the type shown in my copending application, Serial No. 30 1372 filed January 9, 1925. Generator 1 works into coils 2, 3 and 4 connected as shown in Y, which form the primary coils of three grid transformers, the secondaries 5, 6 and 7 of which are also connected in Y 35 and then connected with the grids of vacuum tubes 8, 9 and 10. All grids are shown biased negatively by battery 11, the positive terminal of which is grounded at 12. In series with secondary 7 and the grid of tube 10 is connected the secondary 13 of an audio frequency modulating transformer 14. In series with the primary 15 is microphone 16 and battery 17. By-passing condenser 18 is connected across the secondary 13 of 40 transformer 14. The filaments of the tubes are merely indicated as being grounded at one point 12. The plates of tubes 8, 9 and 10 are connected respectively to inductances 19, 20 and 21 through blocking condensers 50 22, 23 and 24. Inductances 19, 20 and 21 are connected in Y, the common point of which is grounded at 12. The plates are energized from a high potential source 55 represented by battery 25 through high frequency choke coils 26. The negative terminal of battery 25 is grounded at 12. Inductively coupled to coils 19, 20 and 21 are secondary coils 27, 28 and 29 which are connected in series in the proper polarity with 60 respect to the antenna 30 and ground 12.

The operation of the circuit is as follows: From generator 1 through the coupling between the coils 2-5, 3-6, and 4-7, three equal high frequency voltages, differing in 65 phase by 120 degrees, as represented in the

vector diagram of Fig. 2, are applied to the grids of amplifying tubes 8, 9 and 10 which are assumed to be approximately similar in their characteristics. With the output circuits of these tubes properly adjusted and 70 without modulation at microphone 16, no current will flow in the antenna circuit due to the three phase balancing action previously described. When modulation takes place, by voice, for example, at microphone 75 16, the balanced condition is disturbed by virtue of change in characteristics of tube 10 brought about by impressing an audio frequency voltage in the grid circuit, and a pulse of high frequency current of the 80 form given by equation 9 will appear in the antenna circuit. The unmodulated carrier frequency is prevented from reaching the antenna, or is suppressed.

Instead of the load circuit being an antenna it may be a local series circuit as shown in Fig. 3, and composed of inductances 27, 28 and 29, capacity 31, and resistance 32, representing the characteristics 90 of a line wire system.

In Fig. 1 the modulation is effected on the grid of one of the three amplifying tubes in the usual manner. In Fig. 3 is shown a method of effecting modulation on the plate of one tube. In this diagram battery 25 supplies the necessary plate voltage through high frequency choke coils 26 as before. In series with one of these coils however is a very large iron core inductance 33. The plate of the modulating tube 34 is connected 100 to the junction point between inductance 33 and the high frequency choke 26. The grid circuit of tube 34 contains the secondary 35 of a modulation transformer and biasing battery 36. The primary circuit of this 105 transformer contains the primary winding 37, microphone 16, and battery 17. In series with the high frequency choke coils in the D. C. supply to tubes 8 and 9 may be connected the resistances 38, the value of which 110 is equal to the direct current resistance of inductance 33. The function of resistances 38 is to keep the plate voltage applied to tubes 8 and 9 the same as that applied to tube 10, and thus to assist to maintain the 115 high frequency balance of the system although it is not always necessary to employ these resistances.

If a modulating source as, for example, the voice, acts on microphone 16 in accordance with well known theory, the plate voltage applied to tube 10 will vary in accordance therewith and a pulse of current will appear in the load circuit 27, 28, 29, 31 and 32. Due to the balanced properties of the system, an upsetting of the balance in this manner will cause suppression of the unmodulated component of the output current.

While I have shown batteries in each of 120 the cathode circuits and a battery for sup-

plying the anode potential, it will be understood that generators or any other source of energy may be provided and that the symbolic representations are merely for the purpose of illustrating sources of energy. I have illustrated my invention in two embodiments, but it is to be understood that the circuit arrangements shown are only for the purposes of illustrations and that the principles of my invention are broadly adapted for various systems in which a source of multiphase energy is provided and the energy normally balanced in a plurality of circuits. By unbalancing the circuits by modulating the energy on one of its phases I am enabled to impress high frequency energy upon a work circuit of general application while the unmodulated component high frequency carrier wave is suppressed

$$(10) \quad e^t = 0.8E(1+K \sin \rho t) \sin \omega t + E \sin(\omega t - 120^\circ) + E \sin(\omega t - 240^\circ)$$

which states mathematically that two of the three phase voltages have maximum values equal to E , while that of the third is (0.8E) or is less than that value. Equation (10) expanded in the usual manner yields

$$\begin{aligned} e^t &= 0.8E \sin \omega t + 0.8KE \sin \rho t \sin \omega t - 0.5E \sin \omega t \\ &\quad - 0.866E \cos \omega t - 0.5E \sin \omega t + 0.866E \cos \omega t \\ &= -0.2E \sin \omega t + 0.8KE \sin \rho t \sin \omega t \\ (11) \quad &= -0.2E \sin \omega t + \frac{0.8KE}{2} \cos(\omega - \rho)t - \frac{0.8KE}{2} \cos(\omega + \rho)t \end{aligned}$$

which is the form of equation (2) i. e., contains an unmodulated carrier frequency component of reduced amplitude.

The slight degree of unbalancing may be obtained in practice in a number of ways, for example, by having the coupling at one of the input transformers, 2—5, 3—6, or 4—7, or one of the output transformers 19—27, 20—28, 21—29 closer than the coupling of the two remaining transformers, thereby in the first case impressing a higher voltage on the input of one of the amplifying tubes 8, 9, 10, or in the second case developing a higher output voltage from one of the amplifying tubes into the load circuit. As actually observed in practice, in a certain three phase generating unit, arbitrarily unbalanced to a slight degree, the root mean square antenna current during modulation averaged 0.5 ampere while when not modulating the residual antenna current was 0.03 ampere.

Now under certain conditions of operation it is very advantageous not to completely suppress the unmodulated component of the carrier frequency current but to cause to flow in the load circuit or to transmit both during and intermediate the periods of modulation a small fractional amount of the unmodulated carrier component, and it is readily seen that this may be accomplished by means of the methods and circuits outlined herein.

both during and intermediate the signaling periods. I may utilize various methods at the receiving station for restoring the carrier frequency in order to reproduce the received signals in the proper form.

It is evident from a consideration of the circuits shown in Figs. 1 and 3 and from equation (5) that, if the maximum values of each of the three phase voltages are not all equal, at any instant they will not add up to zero. That is, intermediate the modulating periods high frequency current will flow in the load circuit. During modulation an unbalanced condition of this type will also yield an unmodulated component of carrier current, the amplitude of which is proportional to the degree of unbalancing.

For example, equation (6) may be rewritten in the form

$$E \sin(\omega t - 120^\circ) + E \sin(\omega t - 240^\circ)$$

is (0.8E) or is less than that value. Equation (10) expanded in the usual manner yields

While the coils 2, 3 and 4, 5, 6 and 7, and 19, 20 and 21 have been shown connected in star (Y), they may also be connected in delta (Δ). I have illustrated the windings as inductively coupled but I desire that it be understood that other forms of coupling may be used.

Two methods of modulation have been shown in Figs. 1 and 3. It is not intended, however, to limit the scope of this invention to any particular method of modulation, it being understood that any method of modulation acting on one of the three phases so as to disturb a balanced or semi-balanced condition falls within the scope of the appended claims.

What I claim as new and desire to secure by Letters Patent of the United States is as follows:

1. In a high frequency signaling system, the combination of a source of three phase high frequency current, a work circuit, signaling means associated with said source, the said high frequency source, work circuit and signaling means being so associated that both during and intermediate the signaling periods, that component of the high frequency current which is unaffected by the signaling means is suppressed from said work circuit.

2. In a high frequency signaling system, the combination of a source of multi-phase high frequency current, a work circuit, sig-

5 naling means associated with said source, the said high frequency source, work circuit and signaling means being so associated that both during and intermediate the signaling periods, that component of the high frequency current which is unaffected by the signaling means is suppressed from said work circuit.

3. In a high frequency power system, the 10 combination of a three phase source of high frequency current, a plurality of electron tube amplifier circuits, corresponding in number to the number of phases of said source, so associated with said source as to 15 increase the amount of high frequency energy supplied by each phase of the three phase source, a load circuit associated with said electron tube circuits in such a manner as to absorb the high frequency power developed by said circuits, a means of modulation associated with one of said electron tube circuits, said combination so arranged that both during and intermediate the periods of modulation the unmodulated component of the high frequency current is suppressed from said load circuit, but that during said modulation periods, completely modulated high frequency current will flow in said load circuit.

30 4. In a high frequency system, the combination of a three phase source of high frequency energy, a work circuit associated with said source, a modulating means associated with one of the phases of said source, the said three phase source, work circuit and means of modulation so arranged that both intermediate and during the periods of modulation, the unmodulated component of the high frequency current is prevented from flowing in said load circuit, but that during modulation completely modulated high frequency current will flow in said load circuit.

45 5. In a high frequency signaling system, the combination of a three phase source of high frequency energy, a plurality of inductances connected in Δ and energized from said three phase source, a plurality of electron tube circuits corresponding in number to the number of phases of said source, 50 an input circuit for each of said electron tube circuits, inductances in each of said input circuits, said inductances being connected in Δ and inductively coupled with said aforementioned inductances, an output circuit for each of said electron tube circuits, inductances in each of said output circuits, said inductances being connected in Δ , a work circuit inductively coupled with said inductances in said output circuits, 55 said electron tube circuits being normally balanced in such manner that with full high frequency energy supplied from the three phase source to the input circuits of said electron tube circuits all energy is sup-

65 pressed from said work circuit, modulating means associated with one of said electron tube circuits in such manner that when modulating energy is supplied, the balanced condition of said electron tube circuits is disturbed and high frequency energy is supplied to the load circuit only during the period of modulation.

70 6. In a high frequency signaling system the combination of a source of three phase high frequency energy for generating a carrier frequency, a work circuit, signaling means for impressing said energy on said work circuit, and means whereby said energy becomes ineffective to excite said work circuit intermediate the periods of operation of said signaling means for suppressing that component of the carrier frequency which is unaffected by said signaling means from said work circuit.

75 7. In a high frequency electrical system the combination of a substantially balanced source of three phase high frequency energy, a work circuit, and means for disturbing the substantially balanced condition of said source for impressing high frequency energy 80 on said work circuit.

80 8. In a high frequency signaling system the combination of a substantially balanced source of multiphase high frequency energy, a work circuit, and means connected with 95 one of the phases of said substantially balanced source for disturbing the balanced condition of said source whereby high frequency energy may be impressed on said work circuit.

90 9. In a high frequency signaling system the combination of a source of multiphase high frequency energy, a circuit in which said energy is normally substantially balanced, a work circuit connected with said aforementioned means, and signaling means for unbalancing the substantially balanced condition of said first mentioned circuit whereby signaling energy is impressed upon 100 said work circuit.

105 10. A high frequency signaling system comprising in combination a source of multiphase high frequency energy, a plurality of electron tube circuits corresponding in number to the number of phases of said high frequency source, a work circuit, connections between said work circuit and each of said electron tube circuits, said electron tube circuits being normally substantially balanced in such manner that energy from said multiphase source is prevented from reaching said work circuit, and means for unbalancing the substantially balanced condition of said electron tube circuits whereby high frequency energy may be impressed upon said work 115 circuit.

120 11. A high frequency signaling system comprising in combination a source of multi-

- phase high frequency energy, a plurality of electron tube circuits corresponding in number to the number of phases of said high frequency source, a work circuit, connections between said work circuit and each of said electron tube circuits, said electron tube circuits being normally substantially balanced in such manner that energy from said multiphase source is prevented from reaching 5 said work circuit, and means connected with one of said electron tube circuits for unbalancing the substantially balanced condition of said electron tube circuits whereby signaling energy may be impressed upon said 10 work circuit.
12. A high frequency signaling system comprising in combination a source of multiphase high frequency energy, a plurality of electron tubes corresponding in number to 15 the number of phases of said high frequency source, an input and output circuit associated with each of said electron tubes, an inductance in each of said input and output circuits, means connecting the inductances in 20 said input circuits separately with the phases of said multiphase source, a work circuit, means connecting the inductances in each of said output circuits with portions of said work circuit, said input and output 25 circuits being normally substantially balanced in such manner that with high frequency electrical energy supplied from the multiphase source to said electron tubes substantially all of said energy is suppressed 30 from said work circuit, and means for unbalancing the substantially balanced condition of said input and output circuits whereby high frequency energy may be impressed 35 upon said work circuit.
13. A high frequency signaling system comprising in combination a source of multiphase high frequency energy, a plurality of electron tubes corresponding in number to the number of phases of said high frequency source, an input and output circuit associated with each of said electron tubes, an inductance in each of said input and output 45 circuits, means connecting the inductances in said input circuit separately with the phases of said multiphase source, a work circuit, means connecting the inductances in each of said output circuits with portions of said work circuit, said input and output 50 circuits being normally substantially balanced in such manner that with the entire high frequency energy supplied from said source substantially all of said energy is suppressed from said work circuit, and means connected with the circuits of one of 55 said electron tubes whereby the balanced condition of said input and output circuits may be unbalanced for impressing signaling energy upon said work circuit.
14. In a high frequency signaling system 60 the combination of a three phase source of high frequency signaling energy, a plurality of inductances connected in Δ and energized from said three phase source, a plurality of electron tube circuits corresponding in number to the number of phases of 65 said source, an input circuit for each of said electron tube circuits, inductances in each of said input circuits, said inductances being connected in Δ and inductively coupled with said aforementioned inductances, a work circuit, connections between said work circuit and said electron tube circuits, said electron tube circuits being normally substantially balanced in such manner that with 70 the total high frequency energy supplied from said source to said electron tube circuits substantially all high frequency electrical energy is suppressed from said work circuit, and means connected with one of said electron tube circuits for unbalancing the substantially balanced condition of said 75 electron tube circuits whereby signaling energy may be impressed in said work circuit.
15. In a high frequency signaling system 80 the combination of a three phase source of high frequency signaling energy, a plurality of inductances connected in Δ and energized from said three phase source, a plurality of electron tube circuits corresponding in number to the number of phases of said source, an input circuit for each of said electron tube circuits, inductances in each of said input circuits, said inductances being connected in Δ and inductively coupled with said aforementioned inductances, a work circuit, connections between said work circuit and said electron tube circuits, said electron tube circuits being normally substantially balanced in such manner that with 85 the total high frequency energy supplied from said source to said electron tube circuits substantially all high frequency electrical energy is suppressed from said work circuit, and means connected with one of said electron tube circuits for unbalancing the substantially balanced condition of said electron tube circuits whereby signaling energy may be impressed in said work circuit.
16. In a high frequency signaling system 90 the combination of a multiphase source of high frequency signaling energy, circuits connected with said multiphase source for normally substantially balancing the energy supplied therefrom, a single phase work circuit, connections between said single phase work circuit and said aforementioned circuits, and means for unbalancing the normally substantially balanced condition of said first mentioned circuits whereby high frequency signaling energy may be impressed upon said single phase work circuit.
17. In a high frequency signaling system 95 the combination of a multiphase source of

high frequency signaling energy, circuits connected with said multiphase source for normally substantially balancing the energy supplied therefrom, a single phase work circuit, connections between said single phase work circuit and said aforementioned circuits, and means connected with one of said phases for unbalancing the substantially balanced condition of said first mentioned circuits whereby high frequency signaling energy may be impressed upon said work circuit. 10

ROBERT D. DUNCAN, JR.
